COTTON LINTER

Charles R. Carr, Atlanta, Ga., assignor to The Murray Company, Dallas, Tex., a corporation of Texas

Application April 6, 1936, Serial No. 72,929

7 Claims. (Cl. 19—58)

This invention relates to new and useful improvements in cotton linters.

One object of the invention is to provide an improved mechanism for cotton linters, whereby the position of the linter brush and the back wind board, or stripper, may be positively controlled.

An important object of the invention is to provide an improved mechanism for linters which is adapted to be connected with the linter brush 10 and with the wind board of the linter, whereby said brush and board may be simultaneously adjusted with relation to the linter saws, or individually adjusted with relation to each other.

Another object of the invention is to provide an improved mechanism for linters which is manually operable from the exterior of the linter, whereby the linter brush and back wind board of the linter may be moved into various adjusted positions without the necessity of gaining access to the interior of the linter, whereby the adjustments may be made more readily during operation, and with no danger to the operator.

Still another object of the invention is to provide an improved mounting for the brush and back wind board of a linter, which is so constructed that a very fine adjustment of the brush with relation to the linter saws and a fine adjustment of the parts with relation to each other 30 may be easily accomplished.

A further object of the invention is to provide an improved cotton linter having a wind-board which is so constructed that it may be adjusted in a horizontal plane with relation to 35 the linter brush, whereby an increased stripping action is had.

A construction designed to carry out the invention will be hereinafter described, together with the other features of the invention.

40 The invention will be more readily understood from a reading of the following specification and by reference to the accompanying drawings, in which an example of the invention is shown, and wherein:

45 Figure 1 is an enlarged side elevation of a portion of a cotton linter, having an adjusting mechanism, constructed in accordance with the invention applied to the brush and wind board thereof.

50 Figure 2 is a view, similar to Figure 1, showing the shaft bearing in cross-section.

Figure 3 is a transverse, vertical view taken through the linter brush and wind board.

55 Figure 4 is a horizontal, cross-sectional view taken on the line 4—4 of Figure 1, and

Figure 5 is a partial, isometric view, showing one end of the wind board and its connection with the adjusting screw.

In the drawings, the numeral 10 designates a portion of a linter frame which may be of any 5 desired construction. The entire linter has not been shown because it is believed that the invention will be readily understood without such showing. The usual linter saws 11 and brush 12 which is located behind said saws, are mounted transversely within the frame. As is clearly 10 shown in Figure 2, the periphery of the brush revolves in close proximity to the saws 11, whereby said saws are kept clean. It is noted that for efficient operation, the proper distance or space 15 between the saws and brush must be maintained. Since the saws wear, and for various other reasons, the brush must be constantly adjusted.

To provide for a quick and easy adjustment of the brush 12 with relation to the saws, said brush is carried by a transverse shaft 13 which 20 has its outer ends extending through the walls of the linter frame 10. These outer extended ends of the shaft 13 are journaled in bearing boxes 14 which rest on outwardly directed flanges 10' on opposite sides of the linter frame 10. 25 Each bearing box is held in position on the flange by stud bolts 15 which pass through slots 16 in said flange. The bolts are threaded in the base 14' of the box (Figure 1) and receive nuts 17 on their lower ends. It is obvious that when 30 the nuts are loosened on the bolts the bearing boxes 14 may be moved horizontally along the flanges 10'. This horizontal movement of the boxes will move the brush shaft 13 and brush 12 35 accordingly, whereby an adjustment of the brush with relation to the saws 11 may be accomplished.

For readily sliding each bearing box 14 to 40 make the desired adjustment, a horizontally extending bar 18 is provided. The inner end of this bar lies contiguous to the underside of the flange 10' and is provided with an opening 19 through which the rearmost bolt 15 extends. It 45 will be seen that as the bar is moved, with the nuts 17 loosened, the bearing box 14 is slid on the flange 10'.

The outer end of the bar 18 is formed with a threaded shank or rod 20, which is preferably made integral therewith. This rod extends rearwardly of the linter frame and passes through 50 an opening 21' formed in the outwardly extending vertical flange 21 of the linter frame. Lock nuts 22 are threaded on the rod on each side of the flange, and when said nuts engage the 55

flange, the rod 20 and bar 18 are locked in an immovable position, which in turn, holds the box 14, brush shaft 13 and brush 12 in an immovable position. To move said shaft, it is only necessary to change the position of the nuts 22 on the rod 20, whereby said rod and bar 18 may be moved. It is noted that after the nuts 22 have engaged the flange 21, the bar 18, brush shaft and brush are held immovable. To further clamp the bearing boxes to hold the shaft and brush in an adjusted position, the nuts 17 are tightened on the stud bolts.

From the above, it will be seen that a simple and positive adjustment of the linter brush is provided. Also the brush may be moved any desired distance and, therefore, a fine adjustment of the brush with relation to the saw is had. This fine adjustment makes for increased efficiency of the linter.

20 In the rear portion of the linter behind the brush 11, a suitable wind board, or stripper 25 is provided. This wind board may be of any desired construction but it is preferably box-like, being formed of a pair of angular members 26 and 27 which are secured together in any suitable manner. The members are preferably formed of sheet metal and a longitudinal vertical flange 27' is formed along the top of the wind board, while a longitudinal substantially horizontal 30 flange 26' is formed along the lower edge of the same.

The bottom of the wind board is inclined, as is clearly shown in Figures 3 and 5, and a transverse sheet 28 is disposed parallel to this bottom, being spaced therefrom by a suitable filler 28'. This sheet extends the entire length of the board and is fastened to the board by rivets 29. A flexible transverse supporting member 30, has its rear end secured to the rear of the linter frame 40 and extends forwardly therefrom and between the bottom of the board and the sheet 28. The member is of the same length as the board and has its forward end disposed at the same inclination as the inclination of the bottom of the board, 45 whereby this inclined end readily fits in the space between the bottom and the sheet 28. The forward end of the member terminates short of the forward end of the board (Figure 3). With this arrangement, it is obvious that the entire board 50 25 is slidably mounted on the member and may be moved with relation thereto. The windboard thus constructed is cheap in manufacture, and also presents a thin edge adjacent the brush.

To support the windboard within the linter and 55 also to guide said board in a horizontal movement on the supporting member, a plurality of blocks 32 are fastened on the top of the board adjacent the vertical flange 27'. One of these blocks is mounted at each end of the board, while 60 any desired number may be mounted at intervals therebetween.

Each block is formed with a horizontal opening 33 which extends completely therethrough. A guide bolt 34 extends from the rear of the 65 linter frame 10 and passes through the flange 27' and opening 33, and has its other end passing through an angle bar 35 of the frame 10. A nut 36 is screwed onto the end of each bolt 34. Thus, it will be seen that as the windboard 25 is 70 moved, the bolts 34 guide the board in a horizontal direction. The supporting member 30 is sufficiently flexible so that as the board is moved, the member flexes to permit the board to travel in a horizontal plane. It is noted that horizontal 75 movement of said wind board changes its position

with relation to the linter brush 12, whereby a very fine adjustment may be made.

For moving the wind board along its supporting members, an adjusting arm 37 (Figure 5) is mounted on each end of the wind board exteriorly of the linter. Each arm is journaled on the outer end of a bolt 38, which bolt passes through a horizontal slot 39 (Figure 1) in the side wall of the linter. The inner end of each bolt is screwed into a threaded opening 40 in the end block 32. 10 The lower end of the arm carries a collar 41, preferably made integral therewith, and this collar is slidable on the threaded shank or rod 20. A pair of nuts 42 one on each side of the collar are threaded on the rod 20 to hold the collar in 15 various positions thereon.

From the above, it will be seen that by tightening the nuts 42 against the collar 41 and then moving said rod, both the linter brush 12 and wind board 25 may be moved simultaneously. In 20 such case, the position of the board with relation to the brush does not change. If it is desired to adjust only the brush, the nuts 42 are moved away from the collar 41 and the rod 20 moved through the collar, whereby the wind board remains stationary while the brush is moved. Similarly, if it is desired to move the wind board alone, the rod 20 remains in its locked position while the nuts 42 are moved away from the collar 41 on the rod and the collar 41 is slid therealong 25 to move the wind board, after which the nuts are again tightened against the collar 41. Therefore, the mechanism permits the brush and wind board to be moved either simultaneously or separately from each other. All adjustments are 30 made exteriorly of the linter, thereby obviating the necessity of gaining access to the interior. Minor adjustments may be made while the linter is in operation, whereby it is not necessary to halt 40 the operation of the linter, which results in a great saving of time as well as minimizing the possibility of injury to the operator.

What I claim and desire to secure by Letters Patent, is:

1. The combination in a linter having a horizontally movable linter brush and a relatively adjustable wind board, of a mounting including, an adjusting element connected with said brush for moving and holding the same, means for adjustably connecting the wind board with said adjusting element, whereby said brush and board may either be moved and adjusted simultaneously or independently of each other, and means for locking the adjusting element in position to lock the brush and board in various adjusted positions.

2. In a cotton linter, a mounting for the linter brush and wind board of said linter including, movable means connected with the brush for moving and adjusting the same within the linter with relation to the saw element thereof, an adjustable connection between the windboard and said movable means whereby the brush and wind board may be moved and adjusted either simultaneously or independently of each other, and means for locking the movable means in position to lock the brush and board in various adjusted positions.

3. In a cotton linter, an adjustable brush cooperative with the saw elements of the linter, a windboard adjustable with relation to the brush, an adjusting element located on the linter frame, connected to the brush and having provision for adjustably fastening said element to the frame whereby to adjust and hold the brush in position,

and connecting means for adjustably fastening the windboard to said adjusting element whereby the windboard may be adjusted with relation to the brush and the brush and windboard moved individually or together.

5. In a cotton linter, the combination of a brush adjustable with relation to the saw elements, a windboard adjustable with relation to the brush, adjusting means located externally on the linter frame and connected to the brush, means for locking said adjusting means to the frame to hold the brush in adjusted position, and external means adjustably connecting the windboard to said adjusting means whereby to adjust the windboard with relation to the brush and so that the brush and windboard may be moved individually or together.

6. In a cotton linter, a mounting for the linter brush and windboard including, bearings movably mounted on the linter frame and supporting the shaft of the brush, movable supports carrying the windboard, a separate adjusting element connected to each of said shaft supporting bearings, means for adjustably fastening said adjusting elements to the linter frame, and means for adjustably connecting the movable supports of the windboard to said adjusting elements, whereby to adjust the windboard with relation to the brush and so that the brush and windboard may be moved individually or together.

7. In a cotton linter, a transverse shaft, a brush carried by the shaft, bearings slidably mounted on the linter frame and supporting the end portions of said shaft, a windboard having an inclined bottom portion slidably mounted on a flexible support attached to the linter frame, the upper portion of said windboard being slidable on horizontal guide members on the frame and having end projections extended through slots

provided therefor in the opposite sides of the frame, adjusting elements located externally of the frame, connected to the bearings of the brush shaft and having provision for adjustably fastening said elements to the frame whereby to adjust 5 and hold the brush in position, and means for adjustably connecting the windboard end projections to said adjusting elements whereby the windboard may be adjusted with relation to the brush and the brush and windboard moved individually 10 or together.

7. In a cotton linter, an adjustable brush having shaft bearings on the sides of the linter frame, a windboard adjustable with relation to the brush, said windboard comprising a box-like structure 15 including a pair of angular members and having a flat top and an inclined bottom slidable on an inclined flexible plate secured to the linter frame, supports for the upper portion of the windboard slidably mounted on horizontal guide bolts on the 20 frame, projections on the endmost upper supports of the windboard extending through slots provided therefor in the opposite sides of the frame, adjusting bars located externally of the frame, connected to the shaft bearings of the brush and 25 having screw-threaded portions extended through openings in the frame, lock nuts arranged on the screw-threaded portions of said bars to engage the frame to releasably and adjustably lock the bars thereto, adjusting arms attached at their 30 upper ends to the end projections of the windboard and having collars at their lower ends sleeved freely slidable on the screw-threaded portions of said adjusting bars, and lock nuts arranged on the bars to engage the opposite ends of the collars of said adjusting arms to releasably and adjustably lock the arms to the bars.

CHARLES R. CARR.
